Patented Mar. 18, 1975

234,516

DOWN SPOUT ADAPTER

Marty E. Sixt, Iowa City, Iowa, assignor to Advance
Drainage Systems, Inc., Columbus, Ohio

Filed Mar. 29, 1973, Ser. No. 345,876

Term of patent 14 years

Int. Cl. D23—01

U.S. Cl. D23—45

Fig. 2.

Fig. 1.

Fig. 4.

Fig. 3.

FIG. 1 is a side elevational view of a down spout adapter for connecting a rectangular down spout to corrugated tubing showing my new design;

FIG. 2 is a top plan view thereof;

FIG. 3 is a bottom plan view thereof;

FIG. 4 is a side elevational view thereof;

FIG. 5 is a front elevational view of another embodiment of my new design;

FIG. 6 is a top plan view thereof;

FIG. 7 is a bottom plan view thereof;

FIG. 8 is a side elevational view thereof; and

FIG. 9 is a rear elevational view thereof.

I claim:

The ornamental design for a down spout adapter, as shown and described.
